UNITED STATES PATENT OFFICE.

PETER J. WEBER, OF CHICAGO, ILLINOIS.

POST-CAP.

1,059,417.

Specification of Letters Patent.

Patented Apr. 22, 1913.

Application filed July 1, 1912. Serial No. 707,087.

To all whom it may concern:

Be it known that I, PETER J. WEBER, a citizen of the United States of America, and resident of Chicago, Cook county, Illinois, have invented a certain new and useful Improvement in Post-Caps, of which the following is a specification.

My invention relates to the post caps employed in the construction of buildings in which either steel or wood beams are employed for the frames thereof.

Generally stated, the object of my invention is to provide a novel and highly efficient post cap made of iron or steel and adapted for use in supporting the floor girders on the posts or uprights of the frame.

A special object is to provide a novel and improved construction whereby channel iron or steel may be advantageously used for supporting the ends of the girders or other frame members.

It is also an object to provide certain novel features of construction tending to increase the efficiency and serviceability of a post cap of this particular character.

To the foregoing and other useful ends, my invention consists in matters hereinafter set forth and claimed.

In the accompanying drawings—Figure 1 is a side elevation of a post cap embodying the principles of my invention, showing the upper and lower posts and the joists in dotted lines. Fig. 2 is an end elevation of the said cap, showing the posts and joists in dotted lines. Figs. 3 and 4 are similar views, showing how my improved construction may be readily adapted for use as a so-called four way post cap.

As thus illustrated, and referring to Figs. 1 and 2, my invention comprises a pair of side members A of angle iron or steel, said members having vertical flanges a that bear against the sides of the post B and horizontal flanges a¹ that rest upon the top of the said post. If the post is wide enough to require it, a filler plate a² is placed between the edges of the flanges a¹, on top of the said post, the said plate being the same in length as the said side members. The two parallel members A are connected at their opposite ends by means of transverse end bars C, each said end bar being of channel iron with the channel thereof facing upward. These channel irons, or pieces of channel steel, are riveted to the side members A, and serve to

support the ends of the girders D. Each girder is provided at its end with a recess d which engages the inner vertical flange c of the channel iron, and is provided on its lower surface with a transverse notch d¹ which engages the outer vertical flange c¹ of the said channel iron. Thus the girders are not only firmly and solidly supported, but are also tied to the post cap and held against endwise displacement therefrom. As shown in said Figs. 1 and 2, my invention takes the form of a so-called two-way post cap—that is to say, a cap adapted to receive the two opposite ends of one or more girders.

In Figs. 3 and 4, my invention takes the form of a so-called four way post cap—that is to say, a cap adapted to receive the ends of girders and joists. For this purpose the construction is exactly the same as that previously described, except that in this case the side members A are provided with brackets E which are secured to the sides of said members, and which extend a little above the upper edges of the channel iron end bars, or substantially in the plane thereof, the exact form and position of the brackets being unimportant. Each bracket E has a flat top e, and in this way the said brackets are adapted to support the ends of the joists or other frame members F, whereby a so-called four way post connection is made. The seat provided by the top e of each bracket is disposed above the tops of the angle side members A, to support the frame members F in position.

My improved post cap may be used for either steel or wood construction, depending upon the character of the building or structure in which it is employed. The channel iron or steel end bars of the caps are capable of supporting great weight, by reason of the channel formation thereof, and are also, and for the same reason, adapted to tie the girders or other frame members to the posts, and prevent displacement thereof. Also, it will be seen, these channel end bars serve to tie the side members A together, and to prevent a lateral displacement of the latter, whereby the same are held in fixed relation to each other at opposite sides of the top of the post. With this construction the cap can be made to fit any size of post, within limits, without using different materials, and without necessitating the use of different dies or tools. For example, the

space between the flanges a can be two feet, if such is necessary or desirable, or it can be a foot and six inches without using different materials, if this dimension is desirable. The only difference, in each case, will be with respect to the punching of the holes in the end bars C, but otherwise the same materials and the same construction will be employed for caps for posts of different sizes. Moreover, it will be seen that the girders or joists D do not rest upon the side bars A, or upon the filler plate a^2 —that is to say, do not directly engage these elements of construction, but to the contrary are directly engaged only with the end bars C, and with no other parts of the construction. There is, therefore, no direct strain imparted by the structural members to the cap proper, the strain in each case being communicated through a channel iron to the elements which form the cap proper. Consequently, there is no danger of the cap being used in such a manner that the girders or joists do not rest at all upon the channel irons C, or in such manner that the entire weight of the girders and joists is communicated directly to the cap proper, which would be objectionable. Again, and by referring to Figs. 1 and 3, it will be seen that the flanges d of the channel bars overlap the top of the post, whereby the strain on the overhanging portions of the post cap is considerably reduced.

What I claim as my invention is:

1. A post cap comprising angle side members which are spaced apart, and which have inturned flanges that rest on the top of the post, the other flanges of said members embracing the same post, and end bars for connecting together the opposite ends of said members, secured to said inturned flanges, forming seats for the ends of girders, joists or other structural members, and for holding said angle side members in fixed relation to each other, each end bar serving to hold a joist or girder against endwise displacement from the cap.

2. A post cap comprising angle side members which are spaced apart, and which have

inturned flanges that rest on the top of the post, the other flanges of said members embracing the same post, channel end bars for connecting together the opposite ends of said members, secured to said inturned flanges, forming seats for the ends of girders, joists or other structural members, and for holding said angle side members in fixed relation to each other, said channel bars having the channels thereof facing upward, the said joists or other structural members being notched to engage the outer flanges of said channel bars, each end bar serving to hold a joist or girder against endwise displacement from the cap.

3. A post cap comprising angle side members which are spaced apart, and which rest on the top of the post, end bars for connecting together the opposite ends of said members, secured to said inturned flanges, forming seats for the ends of girders, joists or other structural members, and for holding said angle side members in fixed relation to each other, and a filler plate in the plane of said inturned flanges, held against displacement by said end bars, each end bar serving to hold a joist or girder against endwise displacement from the cap.

4. A post cap comprising angle side members which are spaced apart, and which have inturned flanges that rest on the top of the post, the other flanges of said members embracing the same post, end bars for connecting together the opposite ends of said members, secured to said inturned flanges, forming seats for the ends of girders, joists or other structural members, and for holding said angle side members in fixed relation to each other, each end bar serving to hold a joist or girder against endwise displacement from the cap, and the inner edges of said end bars overlapping the top of the post.

Signed by me at Chicago, Illinois, this 26th day of June, 1912.

PETER J. WEBER.
